UNITED STATES PATENT OFFICE.

MARTIN B. McCLEERY, OF PLEASANTVILLE, OHIO.

GAS-STOVE.

SPECIFICATION forming part of Letters Patent No. 731,203, dated June 16, 1903.

Application filed November 12, 1902. Serial No. 130,963. (No model.)

To all whom it may concern:

Be it known that I, MARTIN B. McCLEERY, a citizen of the United States, residing at Pleasantville, in the county of Fairfield and State 5 of Ohio, have invented a certain new and useful Improvement in Gas-Stoves, of which the following is a specification.

My invention relates to the improvement of gas heating-stoves; and the objects of my 10 invention are to provide a simple and inexpensive gas-stove construction by means of which a high degree of heat radiation may be attained by the consumption of a comparatively small amount of gas and to produce 15 certain improvements in details of construction and operation, which will be more fully pointed out hereinafter. These objects I accomplish in the manner illustrated in the accompanying drawings, in which—

20 Figure 1 is a central vertical section of my improved stove, and Fig. 2 is a transverse section on line $\alpha\alpha$ of Fig. 1.

Similar numerals refer to similar parts throughout both views.

25 In carrying out my invention I employ a suitably-supported base-plate 1, from which rises the lower or base portion of the stove 2, which may be cylindrical or otherwise formed in cross-section. The stove-body base portion 2 is surmounted by a horizontally-disposed plate 3, having a central opening therein which communicates with a corresponding opening in the base-plate 1 through a pipe-section or conduit 4. Upon the plate 3 30 and about the opening or conduit 4 is supported a suitable form of ring-burner with which is connected a gas-supply pipe 6, the latter preferably passing upward through the conduit 4 and entering the burner at opposite points through the medium of arms 5^a. The base-drum 2 is provided with a desired number and arrangement of openings or perforations 2^a. Rising from the plate 3 and about the burner 5 is the main drum or cylinder 7 of the stove-casing, this drum preferably being of less circumference than the base portion 2. Depending from an opening in the top plate 8 of the drum 7 is an inner cylindrical casing 9, the latter having formed 45 in its otherwise-closed bottom an opening 10, from which leads upward and outward through said inner cylinder 9 and outer

drum 7 an outlet-pipe 11. Arranged between the internal casing or cylinder 9 and the drum 7 is a suitable casing 12, the open upper termination of the latter being at a point below the top plate 8 of the drum 7, said casing 12 being suitably secured in this position, and preferably by means of bolts 13, which extend between the casings 9 and 12 at desirable intervals. As shown in the drawings, the casing 12 has its lower termination at a point below the bottom of the casing 9, and the bottom plate of said casing 12 is preferably provided with a heat-resisting covering 14, of asbestos or other suitable material. The upper end of the drum 7 is surmounted by a suitable cap-plate 15, in which is provided a desirable arrangement of openings 16. At a point in the drum or casing 7 opposite the burner I provide a doorway and a hinged door 17 therefor.

In operation the products of combustion which rise from the flame at the burner are carried upward in the direction of the arrows 75 to the upper part of the drum 7, thence downward within the drum 12, thence upward and outward through the pipe 11. In this manner heat is imparted in its passage from the burner to the outlet, to the external drum 7, and to 80 both the internal cylinders or casings 9 and 12, with the result that the air which is drawn upward through the passage 4, as indicated by the feathered arrows in Fig. 1, is thoroughly heated before reaching the outlet. It has 85 been demonstrated that the drawing within the stove and the mingling of the fresh air with the products of combustion result in the heated air which is discharged from the pipe 11 being approximately free of burned 90 gas, permitting the stove to be used, if desired, without connection of the pipe 11 with a chimney or other exit to the outer atmosphere. It will also be understood that the heat which is generated within the internal 95 casing 9 will be radiated within the room in which the stove is contained through the top-plate openings 16. It is obvious that the heat generated at the burner will be imparted also to the plate 3 and from the latter radiated 100 within the base-drum 2, from which it will pass outward through the openings 2^a into the room. By the employment of the asbestos covering or plate on the bottom of the cylinder

der 12 it is obvious that said cylinder or casing bottom will be relieved to some extent of the effects of the direct heat from the burner, which is arranged below the same.

5 It will be observed that my improved stove is simple of construction and that the same may be produced at a comparatively low cost.

Having now fully described my invention, what I claim, and desire to secure by Letters

10 Patent, is—

In a gas-stove, the combination with a base drum or casing 2, a main casing or drum 7 surmounting said base-drum, a plate between said upper and lower drum portions, said 15 plate having an opening therein which communicates with a passage 4 extending through

the base-drum and a ring-burner mounted upon said drum-supporting plate about said passage 4, of an internal casing 9 having its upper open end depending from an opening 20 in the top plate of the drum or casing 7, an outlet-pipe leading from an opening in the bottom of the casing 9 thence out through the external casing or drum 7 and a casing 12 arranged between the casings 7 and 9 and extending below the latter, substantially as specified.

MARTIN B. McCLEERY.
